UNITED STATES PATENT OFFICE.

HARRY F. GEIST, OF RACINE, WISCONSIN, ASSIGNOR, BY MESNE ASSIGNMENTS, TO WEBSTER ELECTRIC COMPANY, OF RACINE, WISCONSIN, A CORPORATION OF WISCONSIN.

MAGNETO-MACHINE.

1,275,901.

Specification of Letters Patent. Patented Aug. 13, 1918.

Application filed May 20, 1916. Serial No. 98,903.

To all whom it may concern:

Be it known that I, HARRY F. GEIST, a citizen of the United States, residing at Racine, in the county of Racine and State 5 of Wisconsin, have invented a certain new and useful Improvement in Magneto-Machines, of which the following is a full, clear, concise, and exact description, reference being had to the accompanying drawings, forming a part of this specification.

My invention relates to dynamo electric machines, and more particularly to magneto machines capable of being used for ignition purposes in association with internal combustion engines. Although my invention is particularly applicable to ignition magnetos it will be understood that the underlying principle upon which my hereinafter described machine operates is not limited 20 solely to ignition magnetos, but may be incorporated in magneto machines of other classes.

A magneto machine constructed in accordance with and embodying the teachings 25 of my present invention is efficient, may be cheaply manufactured, and may be so arranged that its several component parts occupy a minimum space, thus affording a compact magneto structure.

I believe the novel features of my invention will most readily be understood from a description read in connection with the drawings illustrating my invention. I shall, therefore, proceed at once to a detailed description of the drawings wherein Figure 1 35 is a more or less diagrammatic view which illustrates the general construction of a magneto machine embodying my invention;

Fig. 2 is an axial sectional view of a high 40 tension magneto constructed in accordance with my invention;

Fig. 3 is an end view of the magneto with the permanent and removable end plates detached more clearly to illustrate the interior 45 construction;

Fig. 4 is an end view of the magneto machine of Figs 2 and 3 with a portion of the removable end plate broken away to illustrate how the coil carrying cores are secured 50 in position, the housing for the interrupter devices being shown in section to reveal the parts therein contained;

Fig. 5 is a vertical sectional view taken on the line 5—5 of Fig. 2 and looking in the 55 direction indicated by the arrows;

Fig. 6 is a diagrammatic representation of the circuit connections desirably employed in a machine of the type shown in Figs. 2 to 5 inclusive;

Fig. 7 is an isolated view in perspective 60 of a modified form of the rotor;

Fig. 8 is a horizontal sectional view taken through the pole pieces of a machine provided with a further rotor modification;

Fig. 9 is a side elevational view of a modified form of magneto machine embodying 65 certain features of my present invention;

Fig. 10 is a vertical axial sectional view 70 of the machine illustrated in Fig. 9; and

Fig. 11 is a vertical sectional view taken 75 on the line 11—11 of Fig. 10 and looking in the direction indicated by the arrows.

Similar characters of reference refer to similar parts throughout the several views.

Referring first to the diagrammatic showing of Fig. 1, 20 illustrates a base plate of any suitable non-magnetic material upon which is mounted a pair of U or horse shoe permanent magnet sets 21—21 and 22—22. It will be noted that the magnets of the sets 80 21—21 and 22—22 are disposed side by side and spaced apart with the corresponding poles of the permanent magnet sets located adjacent the same side of the base plate 20. The magnet sets 21—21 and 22—22 are at 85 their respective poles provided with pole pieces having suitable curved faces whereby the pole pieces are arranged to coöperate with a novel form of rotor presently to be described. The pole piece situated at what 90 we may say are the north poles of magnets 21—21 is indicated by reference characters 21—N, the other pole piece of the permanent magnet sets 21—21 being indicated by reference characters 21—S. The corresponding pole pieces of magnet set 22—22 95 are respectively indicated at 22—N and 22—S.

The pole pieces 21—N and 22—N support and are connected by a coil carrying core 23, 10 and the pole pieces 21—S and 22—S support and are connected by a similar coil carrying core 24, the coil carrying cores as shown in this figure having their extremities conformed to rest upon the tops of their 10 associated pole pieces. The cores 23 and 24 are provided with suitable generating windings illustrated at 25 and 26 respectively. Inasmuch as the purpose of Fig. 1 is merely 11 to enable a clear understanding of the op-

eration of the machine I have not in this figure shown any of the devices whereby the several parts of machine are fastened in position, nor have I illustrated all of the operating parts in all of their detail.

Operating around an axis spanned by the magnets is a rotor 27, the shaft of which is journaled in suitable end plates (not shown). This rotor is constructed of magnetic material and at its ends is provided with arms, or projections, 27^a and 27^b located 180° apart and provided with convex extremities arranged when the rotor is operated to sweep past the pole pieces of the magnet sets. It will be seen that the rotor arm 27^a operates in proximity to the pole pieces 21—N, 21—S of the permanent magnet set 21—21, whereas the rotor arm 27^b operates in proximity to the pole pieces 22—N and 22—S of the magnet set 22—22. It will be understood that the generating windings 25 and 26 are suitably connected in circuit in any approved manner, not shown.

25 In the operation of the machine when the rotor is revolved each of the rotor arms is carried past first one and then the other of the pole pieces with which it co-operates. When the rotor is in the position shown in 30 Fig. 1 a magnetic circuit, including the core of the generating winding 25, may be traced from pole piece 21—N through coil carrying core 23 to pole piece 22—N, thence over magnets 22—22 to pole piece 22—S, and 35 thence through rotor 27 back to pole piece 21—N from whence we started to trace the magnetic circuit. In a like manner a magnetic circuit including the core of the generating winding 26 may be traced from pole 40 piece 22—S through coil carrying core 24 to pole piece 21—S, thence over magnets 21—21 to the pole piece 21—N and through rotor 27 back to pole piece 22—S from whence we started to trace this particular magnetic 45 circuit. When the rotor arms 27^a and 27^b leave the pole pieces 21—N and 22—S the magnetic circuits just referred to may no longer be traced, causing a sudden decrease in the magnetic lines traversing the cores of 50 the generating windings 25 and 26. Moreover, when the rotor is turned to such a position that the arms 27^a and 27^b are respectively brought opposite the pole pieces 21—S and 22—N magnetic circuits, including 55 the cores of the generating windings, may again be traced but this time the flux direction through the cores is opposite to what it was before with the result that the current induced in the generating windings 60 when the rotor arms sweep past pole pieces 21—S and 22—N is opposite in direction to the current induced in the generating windings when the rotor arms sweep past the 65 poles of the pole pieces 21—N and 22—S. Thus, the rotation of the rotor 27 serves to

generate an alternating current either or both waves of which may be utilized for ignition purposes.

In utilizing for ignition purposes the principle of magneto operation just described I prefer that the machine shall be of the high tension type. For the purpose of clearness I have not, in Fig. 1, shown many of the features which characterize a high tension magneto machine, but I shall now proceed to take up the description of a high tension machine embodying my invention. It will be understood, of course, that many of the features of this high tension machine are just as applicable to a low tension machine as they are to one which develops a high tension current.

In Figs. 2 to 5, inclusive which illustrate the structural features of a high tension machine, reference numeral 30 indicates the base of the machine, which base may be solid or in the form of a hollow casting, and 31—31 the magnets of the two spaced sets. Each of the four pole pieces is indicated by the reference numeral 32, each of the pole pieces comprising a plurality of vertically disposed laminæ, as is most clearly illustrated in Fig. 2. It will be noted that a considerable number of the laminæ which compose each pole piece are given the conformation illustrated in Fig. 3, that is, they extend upwardly beyond the curved face of the pole piece to constitute an upwardly projecting laminated arm 33—33 against which the adjacent end of an associated coil carrying core may abut in a manner presently to be described. The pole pieces of like polarity are spaced apart by a plate 34 of non-magnetic material which has a central opening therethrough to accommodate the rotor. By referring to Fig. 5 it will be seen that the plate 34 extends beyond the pole pieces on each side of the structure to constitute abutments for the magnets 31 which span the pole pieces and have their extremities lying in the spaces between the plate 34 and the permanent end plates 35—35. Each of the end plates 35—35 is provided with a pair of upwardly extending arms 36—36, the purpose of which will presently be explained. The pole piece laminæ, plate 34 and end plates 35—35 are rigidly secured together by means of a plurality of rivets 37—37. Some of these rivets are iron and hold individual pole piece laminæ together, others being brass for machine assembling. The laminæ constituting each of the upwardly extending pole piece arms 33—33 are at their upper ends secured together by rivets 38—38, as shown in Fig. 3. The permanent end plates are desirably secured to the base 30 by screws or rivets, as indicated at 39—39 in Fig. 3.

Each of the coil carrying cores which are illustrated at 40—40, comprises a plurality 130

of horizontal soft iron laminæ and, as is most clearly shown in Fig. 2, a number of the middle laminæ of each core terminate some distance short of the ends of the core to provide bifurcated core ends 41—41. A screw 42 projects through each bifurcated core end and engages in the adjacent upwardly extending permanent end plate arm 36.

10 The screws 42—42, therefore, serve not only to secure the coil carrying cores to the permanent end plates, but also serve to draw each core tightly into engagement with the upwardly extending arms 33—33 of its associated pole pieces. Carried upon each of the laminated cores 40—40 are the primary and secondary windings illustrated at 43—43 and 44—44 in Fig. 5.

15 The permanent end plates 35—35 have circular openings therein to permit the insertion of the rotor, etc., and projecting into said openings are circular bosses formed upon removable end plates 45—45, each of which is secured to its associated permanent end plate by screws, as illustrated. The removable end plates 45—45 serve to journal the rotor and may be provided with suitable lubricating devices, one of which is illustrated at 46 in Fig. 2. The rotor forming a 20 part of the machine illustrated in Figs. 2 to 5 inclusive is in shape generally similar to the rotor described in connection with Fig. 1 and consists of a plurality of soft iron laminæ 47 which are by means of rivets 25 clamped between members 48—48, each of which is secured to or formed integral with a shaft section 49 journaled in one of the removable end plates 45. The members 48—48 and interposed laminæ are conformed 30 to provide a rotor having arms 180° apart, with convex extremities arranged to sweep past the curved faces of the laminated pole pieces 32—32. Secured upon one of the shaft sections 49 is a spur gear 50 whereby 35 the rotor may be driven from the engine with which the magneto is associated.

40 As is most clearly shown in Figs. 2 and 4, a plate 51 of insulating material is secured to one of the end plates 45 and pivoted upon the plate 51 is a bell crank lever 52, one arm of which carries a movable interrupter contact arranged to engage with a stationary contact supported by the plate 51. The interrupter contacts are normally held 45 closed by means of a spring 53 acting between the bell crank lever 52 and a small bracket carried by the plate 51. It will be understood that the stationary interrupter contact is desirably connected with the insulated side of the primary circuit and that the movable interrupter contact is grounded to the magneto frame as is usual in magneto 50 construction.

55 Keyed upon the adjacent shaft section 49 is a collar 54 carrying cams 55—55 disposed

180° apart and adapted when the rotor is operated to engage with the power arm of the bell crank lever 52 to separate the interrupter contacts. I will at this point state that the collar 54 is so located with respect 70 to the rotor arms that the cams 55—55 operate to effect the separation of the interrupter contacts just as the rotor arms are leaving the faces of the pole pieces over which they are caused to sweep. The interrupter devices just described are conveniently inclosed in a housing indicated at 56.

75 Resting upon the top of the windings is a plate 57, preferably of insulating material, which supports a condenser 58 of any suitable design. The condenser is retained in position and partially inclosed by a sheet metal cap or cover indicated at 59.

80 The circuit arrangement is diagrammatically illustrated in Fig. 6 and it is not 85 thought that any particular explanation thereof is required except to say that an ordinary sparking plug is illustrated at 60. In this figure the windings, condenser, etc., are indicated by the same reference numerals as have been used in Figs. 2 to 5.

85 In so far as the generation of current in the primary circuit is concerned the magneto illustrated in Figs. 2 to 6 operates exactly as does the magneto diagrammatically 90 illustrated in Fig. 1, the operation of which has been described in considerable detail. Twice during each revolution of the rotor of the high tension magneto and just at the peak of the current wave created in the primary windings, that is, when the rotor arms are leaving the polar faces over which they have been sweeping, the interrupter contacts are opened and the condenser operates with the result that a spark is caused to pass at 95 the sparking plug 60 in a manner well known in the art.

100 The modified form of rotor illustrated in Fig. 7 does not differ essentially from the rotor of the device illustrated in Figs. 2 to 5, 105 except that instead of consisting partially of laminated metal and partially of solid plates, the rotor of Fig. 7 is formed of one solid piece of metal, and, as illustrated, the edges of the rotor arm extremities have a 110 plurality of parallel slits 61 formed therein to secure in part at these points the advantages afforded by a laminated structure.

115 In the arrangement shown in Fig. 8 the magnets are shown at 62—62, the pole pieces at 63—63, and the spacer between the pole pieces is shown at 64. The rotor shown in this figure differs from the rotors previously 120 described in that it consists of two shaft sections 66—66, each of which carries or is formed integral with an oblique plate 67. Clamped between the oblique plates 67, by rivets or otherwise, are a plurality of flat laminæ 68—68 which at their extremities are 125 conformed to present faces substantially 130

similar to the extremities of the rotor arms illustrated in the preceding figures. The rotor shown in Fig. 8 affords certain advantages from a manufacturing standpoint.

5 The magneto machine illustrated in Figs. 9 to 11, both inclusive, operates upon the same general principle as do the magnetos illustrated in the preceding figures, but differs considerably therefrom in its structural 10 make-up. In this species of my invention the base plate is illustrated at 70, the horse shoe magnets at 71—71, and the top plate at 72. Located between the base plate 70 and the top plate 72 and disposed in engagement with the proper magnet poles are the four pole pieces each of which is indicated as a whole by the reference numeral 73. Each of the pole pieces 73 has its polar face conformed to coöperate with the arms of a 15 rotor and consists of a pair of upper and lower blocks 74 and 75 separated by soft iron laminæ 76. There are thus two sets of the laminæ 76, each set being common to two of the pole pieces, that is, one set being 20 common to the pole pieces of one polarity and the other set of laminæ being common to the pole pieces of opposite polarity. The laminæ 76, which correspond to the coil carrying cores of Fig. 1, are reduced in width 25 intermediate the pole pieces to accommodate the generating windings 77—77. As is most clearly shown at 78—78 in Fig. 9 the blocks 74 and 75 and the laminæ 76 are conformed to present shoulders between which and the 30 adjacent end plates the magnets are disposed, the magnets in the present case being cut away to accommodate the shoulders 78. The rotor shown in this figure may be formed in one piece, as shown, or may be 35 of the construction illustrated in either Figs. 2 to 5, Fig. 7 or Fig. 8 as desired. The magneto shown in Figs. 9 to 11 operates in all material respects in substantially the 40 same manner as does the magneto illustrated 45 in Fig. 1.

Attention is called to the fact that the machine of my invention produces two current impulses per revolution and affords a broad current wave which facilitates timing.

50 These are important and advantageous features of my machine.

Having now described the principle of operation peculiar to my improved form of magneto machine, as well as the structural 55 make-up of a number of embodiments of my invention, what I claim as new and desire to secure by Letters Patent of the United States is:

1. A magneto machine comprising a pair 60 of horse shoe magnets disposed side by side with their poles extending in the same direction, a pole piece located on the inner face of each magnet at each pole thereof, two coil carrying cores, one connecting the pole 65 pieces of one polarity and the other core

connecting the pole pieces of the opposite polarity, a generating winding in inductive relation to each of said cores, and a rotor operating in the space between the magnet poles arranged when operated to afford a 70 path for magnetic flux between the north pole of one of the said magnets and the south pole of the other magnet, and then to provide a path for magnetic flux between the south pole of the first magnet and the 75 north pole of the second magnet.

2. A magneto machine comprising a pair of horse shoe magnets disposed side by side with their poles extending in the same direction, two coil carrying cores, each core connecting a pole of one magnet with the corresponding pole of the other magnet, a generating winding in inductive relation to each of said cores, and means operating in the space spanned by the magnets arranged 80 when operated successively to establish a magnetic path between the north pole of one magnet and the south pole of the other magnet, and then a magnetic path between the south pole of the first magnet and the 85 north pole of the second magnet.

3. A magneto machine comprising a pair of permanent horse shoe magnets disposed side by side with their poles extending in the same direction, a coil carrying core connecting a pole of one magnet with the corresponding pole of the other magnet, a winding in inductive relation to said core, and means operating in the space spanned 90 by the magnets arranged successively to establish and interrupt a magnetic path between the north pole of one magnet and the 95 south pole of the other magnet.

4. A magneto machine comprising a pair of horse shoe magnets disposed side by side 100 with their poles extending in the same direction, a coil carrying core connecting a pole of one magnet with the corresponding pole of the other magnet, and a rotor operating in the space spanned by the magnets arranged 105 successively to establish and interrupt the magnetic paths between the poles of one magnet and the opposite poles of the other magnet.

5. A magneto machine comprising a pair 110 of permanent magnets with their poles extending in the same direction, a pole piece for each pole of each magnet, two coil carrying cores, one connecting pole pieces of one polarity and the other connecting pole pieces 115 of the opposite polarity, a generating winding in inductive relation to said cores, and a rotor arranged when operated successively to establish and interrupt a path for magnetic flux between the south pole of one magnet and the north pole of the other magnet.

6. A magneto machine comprising in combination a base, a pair of permanent horse shoe magnets disposed upon the base with their poles extending in the same direction 120

and with the north poles thereof on one side of the base and the south poles thereof on the other side of the base, a pole piece for each pole of said magnets, an unwound rotor 5 of magnetic material revoluble in the space spanned by the magnets and provided with two arms substantially 180 degrees apart, whereby when the rotor is revolved it successively establishes and interrupts magnetic paths between pole pieces of different 10 magnets and of different polarity, a pair of parallel coil carrying cores, one core connecting pole pieces of one polarity and the other connecting pole pieces of the opposite 15 polarity, and a generating winding in inductive relation to each of said cores.

7. A magneto machine comprising in combination a pair of horse shoe magnets disposed side by side, a pole piece at each of 20 the poles of each of said magnets, each pole piece comprising a curved polar face and an upwardly projecting arm, a rotor movable in the space spanned by the magnets and arranged when rotated to establish and 25 interrupt a magnetic path between the north pole of one magnet and the south pole of the other, and to successively establish and interrupt a magnetic path between the south pole of the first magnet and the north pole 30 of the second magnet, a pair of coil carrying cores, each core disposed parallel to the axis of the rotor and connecting the upwardly extending arms of two pole pieces of similar polarity and a generating winding 35 in inductive relation to each of said cores.

8. A magneto machine comprising a pair of U shaped magnets disposed side by side, a pole piece for each pole of each of said 40 magnets, each pole piece comprising a curved polar face and a pair of said pole pieces of similar polarity having upwardly projecting arms, a rotor operating in the space spanned by the magnets arranged when rotated successively to establish and interrupt a magnetic 45 path between the north pole of one magnet and south pole of the other magnet, a coil carrying core extending between and connecting the upwardly extending pole

piece arms aforesaid, and a generating winding in inductive relation to said cores.

9. A magneto machine comprising in combination a pair of U shaped magnets disposed side by side, with their poles extending in the same direction, a pole piece for 55 each pole for each of said magnets, a rotor operating in the space spanned by the magnets and arranged when operated successively to establish and interrupt a magnetic path between one pole piece and the diametrically opposite pole piece, and then to establish a magnetic path between the other pole pieces, a core disposed parallel to the axis of the rotor and connecting a pair of pole pieces and generating winding in inductive relation to said core.

10. A magneto machine comprising in combination with a pair of permanent horse shoe magnets disposed side by side, with their poles extending in the same direction, 70 each magnet pole provided with a pole piece having a concave polar face, an unwound rotor arranged to be rotated in the space between the magnet poles and provided with two arms 180 degrees apart, one of said arms arranged to sweep past the pole pieces of one magnet and the other arm arranged to sweep past the pole pieces of the other magnet, a pair of coil carrying cores, each core connecting pole pieces of similar polarity 75 80 and a generating winding in inductive relation to each of said cores.

11. A generator comprising a pair of U shaped magnets disposed side by side with their poles extending in the same direction, 85 a core piece connecting the pole of one magnet with the corresponding pole of the other magnet, and means for alternately completing and interrupting the magnetic path between one pole of one magnet and the pole of opposite polarity of the other magnet.

In witness whereof, I hereunto subscribe my name this 16th day of May, A. D. 1916.

HARRY F. GEIST.
